[57] CLAIM

The ornamental design for a video game machine, as shown and described.

DESCRIPTION

FIG. 1 is a front, top and right perspective view of a video game machine showing my new design; FIG. 2 is a rear, bottom and left perspective view thereof;

FIG. 3 is a front elevational view thereof;

FIG. 4 is a rear elevational view thereof;

FIG. 5 is a right side elevational view thereof, a left side being a mirror image;

FIG. 6 is a top plan view thereof;

FIG. 7 is a bottom plan view thereof;

FIG. 8 is a front, top and right perspective view of a second embodiment of FIG. 1;

FIG. 9 is a rear, bottom and left perspective view of FIG. 8 thereof;

FIG. 10 is a front, top and right perspective view of a third embodiment of FIG. 1;

FIG. 11 is a rear, bottom and left perspective view of FIG. 10 thereof;

FIG. 12 is a front, top and right perspective view of a fourth embodiment of FIG. 1 thereof;

FIG. 13 is a rear, bottom and left perspective view of FIG. 12 thereof;

FIG. 14 is a front, top and right perspective view of a fifth embodiment of FIG. 1;

FIG. 15 is a rear, bottom and left perspective view of FIG. 14 thereof;

FIG. 16 is a front, top and right perspective view of a sixth embodiment of FIG. 1;

FIG. 17 is a rear, bottom and left perspective view of FIG. 16 thereof;

FIG. 18 is a front, top and right perspective view of a seventh embodiment of FIG. 1; and,

FIG. 19 is a rear, bottom and left perspective view of FIG. 18 thereof.
